UNITED STATES PATENT OFFICE.

ROBERT W. SCOTT, OF PHILADELPHIA, PENNSYLVANIA, ASSIGNOR OF ONE-HALF TO LOUIS N. D. WILLIAMS, OF ASHBOURNE, PENNSYLVANIA.

MAGAZINE-FIREARM.

SPECIFICATION forming part of Letters Patent No. 680,207, dated August 6, 1901.

Application filed January 30, 1901. Serial No. 45,355. (No model.)

To all whom it may concern:

Be it known that I, ROBERT W. SCOTT, a citizen of the United States, residing in Philadelphia, Pennsylvania, have invented certain Improvements in Magazine-Firearms, of which the following is a specification.

The object of my invention is to provide a simple, convenient, and effective means whereby a number of cartridges constituting the magazine charge for a modern rifle can be conveniently carried and introduced rapidly and with accuracy into a magazine having a side opening—such, for instance, as that of the United States magazine-rifle, caliber .30" and others of the same class. This object I attain in the manner hereinafter set forth, reference being had to the accompanying drawings, in which—

Figure 1 is a plan view of sufficient of a magazine-rifle to illustrate the manner of loading the magazine with cartridges in a clip in accordance with my invention, the side gate being open and the clip of cartridges adjusted into position to permit the cartridges to be pushed from the clip into the magazine. Fig. 2 is a view, partly in elevation and partly in transverse section, on the line $a-a$, Fig. 1, looking rearwardly or toward the stock of the gun. Fig. 3 is a similar view showing the cartridges being pushed into the magazine; and Fig. 4 is a view of part of the side gate for closing the magazine of the gun, this view illustrating a special feature of my invention.

In rifles of the United States magazine .30" caliber type the magazine 1 is below the channel in which works the longitudinal bolt whereby the cartridge is pushed into the breech end of the barrel and the empty shell is extracted therefrom, such magazine opening at the right-hand side of the action, at which point there is a swinging gate 2 for closing said open end of the magazine, this gate having a spring-follower 2^a for feeding the cartridges across the platform formed by the bottom of the magazine, so as to bring them successively into range of the longitudinally-reciprocating breech-bolt.

In an application for patent filed by me on the 10th day of December, 1900, Serial No. 39,387, I have shown, described, and claimed a cartridge-clip for use in connection with a

magazine-rifle of the character specified, such clip consisting of a plate of sheet metal having at each edge L-shaped flanges 4, forming guides for the heads of the cartridges, said 55 clip containing a spring-plate 5 for bearing upon said heads and exerting such pressure thereupon as to prevent their accidental release from the clip.

To insure the proper feeding of the cartridges into the magazine, it is necessary that the clip shall be held with comparative rigidity in the direction of the length of the gun, and for this reason I form in the flange 10, with which the swinging gate 2 is provided, a 65 notch 11, into which the edge of the clip can be entered and which serves not only to hold the clip at a proper angle in respect to the magazine, but also to prevent the bullet held in the neck of the cartridge from coming into 70 contact with the platform or floor of the magazine, as would be the case if the charged clip was not prevented by the restraining influence of the guide-notch in the gate from tilting forwardly and downwardly.

Obviously if the bullet end of the cartridge should rest on the platform before the head of the cartridge had passed out of the clip part of the pressure required for stripping the cartridges from the clip would be sustained by the bullet end of the lowermost cartridge, and this would result in locking the rim of the cartridge under the flanges of the clip, and thus prevent the free delivery of the cartridges from the clip and into the magazine. 85

It will be noted that in the use of my improved clip the cartridges are introduced into the magazine by pressure and not, as in ordinary practice, by their own gravity, for when the latter method is adopted there is danger in the case of rim-cartridges of the rim of the leading cartridge overlapping the rim of the next following cartridge. Hence when the edge of the bolt contacts with the rim of the leading cartridge when about to carry it forward and into the chamber of the gun the pressure is really exerted upon both the leading cartridge and the following cartridge, which its rim overlaps, and as the cartridge not directly engaged by the bolt is still below 95 the exit-aperture of the magazine a jam results, and under the pressure applied the

rims of one or both cartridges may be torn away, making subsequent extraction uncertain, or the projectile of the cartridge which is below the exit-aperture of the magazine

5 may be forced back upon the explosive charge of the cartridge, so as to compress the latter and cause excessive generation of pressure when it is fired.

Besides forming the notch 11 in the flange 10 of the swinging gate to constitute a guide and retainer for the outer edge of the clip I prefer also to form a notch or guide 15 in the upper lip of the mouth of the magazine, this notch receiving the upper edge of the clip, 15 and thus providing for the rigid longitudinal retention of both edges.

Instead of providing the swinging gate with the guide-notch I may adopt other means. For instance, I may have a spring-arm 12, 20 mounted upon the gate and having a guide-notch 11 formed in it, as shown in Fig. 4, for the reception of the edge of the clip, the spring-arm being pushed back into its recess when the swinging gate is closed.

25 The spring-arm has a beveled cam-surface 13 in the rear of the notch, so that the operator may more readily guide the edge of the clip into the notch by sliding the clip up over said beveled cam-surface.

30 When the swinging gate has been opened, as shown in Fig. 1, and the clip with its charge of cartridges has been entered in the guide-notches, the cartridges can be instantly forced from the clip into the magazine by the pressure of the thumb on the outermost cartridge 35 of the row, as in Fig. 2, and as this pressure is continued the thumb swings down in front of the clip and the latter is gradually raised until when the last cartridge is passing into 40 the magazine the clip will be substantially vertical, as shown in Fig. 3, whereupon a rearward movement of the thumb ejects the

empty clip, while at the same time the raising movement of the hand closes the gate and brings the firearm into condition to deliver 45 the magazine charge.

Having thus described my invention, I claim and desire to secure by Letters Patent—

1. A magazine-gun having a swinging gate 50 for closing the magazine, said gate having a guide-notch and bearing such relation to the side of the magazine that it will receive the edge of a cartridge-clip introduced between the magazine and gate, and bearing upon the 55 side of the magazine.

2. A magazine-gun having a swinging gate for closing the magazine, said gate and the upper lip of the mouth of the magazine having notches for receiving the edges of a cartridge-clip when the latter is adjusted to deliver its charge of cartridges into the magazine. 60

3. A magazine-gun having a swinging, magazine-closing gate, with spring-actuated bar 65 or plate having a guide-notch for the reception of the edge of a cartridge-clip when the latter is adjusted to deliver its cartridges into the magazine.

4. A magazine-gun having a swinging, magazine-closing gate, with guide-notch for the reception of the edge of a cartridge-clip when the latter is adjusted to deliver its cartridges into the magazine, and a beveled cam in rear of said notch for directing the edge of the 75 clip into the same.

In testimony whereof I have signed my name to this specification in the presence of two subscribing witnesses.

ROBERT W. SCOTT.
